(57) **CLAIM**

The ornamental design for “crown head hair roller,” as shown.

DESCRIPTION

FIG. 1 is a perspective view of a “crown head hair roller” showing my new design;

FIG. 2 is a front view thereof, the rear view being identical thereto;

FIG. 3 is a right side view thereof, the opposite side being identical thereto; and,

FIG. 4 is a top plan view thereof; the bottom plan view being the mirror image thereof.
